UNITED STATES PATENT OFFICE.

WILLIS A. FOGG, OF MALDEN, MASSACHUSETTS.

WICKET FOR HOUSE-DOORS.

1,186,566.

Specification of Letters Patent. Patented June 13, 1916.

Application filed October 15, 1914. Serial No. 866,853.

To all whom it may concern:

Be it known that I, WILLIS A. FOGG, a citizen of the United States, and a resident of the city of Malden, in the county of Middlesex and Commonwealth of Massachusetts, have invented certain new and useful Improvements in Wickets for House-Doors, of which the following is a full, clear, and exact specification.

10 This invention relates to wickets or small closable openings in dwelling-house doors for permitting the introduction of milk, provisions and other articles without the necessity of opening the large door provided with 15 the same; and it has for its object the effecting of certain improvements in details of construction hereinafter set forth, and illustrated in the drawings forming part of this specification, in which—

20 Figure 1 is a perspective view of a portion of a door provided with a wicket embodying my improvements. Fig. 2 is a vertical section of the same.

Referring first to Fig. 1, the numeral 1 25 designates a dwelling-house, or other, door of usual construction, having two horizontal panels in its lower portion, and vertical panels in its upper part. While I do not restrict my wicket to this type of doors, since 30 it may be applied to doors having vertical lower panels, yet I prefer to show it in connection with what is now the prevailing style in houses of medium cost.

In applying my wicket to either type of 35 door in which the panels are not too large, the entire lower panel is removed; in the case of the horizontal paneled door, the lowest panel is taken out, while in the case of the vertical paneled door, the lowest panel 40 nearest the hinges is removed. The lowest horizontal panel having therefore been cut out, and the moldings removed which surrounded the same, the door is ready for receiving my wicket, which is preferably constructed entirely of wood.

The wicket-door 2 consists of a single board of substantially the same thickness and appearance of the panel removed, and painted or stained to match the remainder 50 of the wood-work.

The wicket-casing consists of two frames. The inner frame 3 is the one which is applied to the inner side of the house door, and the outer frame 4 is applied to the outside of 55 the house door.

The inner frame comprises a top, two sides and a lower member or water-shed. The top 5, and sides 6 are of like cross-section, consisting in each case of a length of wood molded to have a flange or shoulder 9, 60 a rabbet 10, and a deep groove or slot 11; the rabbet is designed for the reception of the edges of the wicket-door 2; and the flange or shoulder is designed to fit against the inner surface of the portion of the house-door surrounding the panel-opening. 65

The bottom member or water shed 12 is deeper than the other members of the inner frame, having its upper surface slanting downward from its inner and raised edge 13, 70 while its under surface is cut partly away to receive the edge of the door opening, and to provide an overhang 14.

The ends of the top member 5 and the upper ends of the side members 6, are mitered 75 to fit each other, as indicated in Fig. 1, and said parts are preferably fastened to the inner surface of the house-door by screws 15 penetrating the shoulders 9 into the door 1. The water-shed, when made with the overhang 14, must be applied to the door-opening separately, and is fastened therein by screws or brads passing vertically downward into the house-door. Without the overhang, the water-shed 12 can be attached 80 originally to the side members before the entire inner frame is put in place. 85

The outer frame 4 consists of three members,—a top 16, and two sides 17,—all of like cross section. Such cross section is in 90 the shape of a letter L, having a front strip 19 designed to be fastened to the outer surface of the door 1 about the panel-opening, and a flange 20 fitted to enter the groove or slot 11 of the inner frame. This flange and 95 groove are made of sufficient depth to enable the same to be in engagement whether the material composing the door 1 is thin or thick. If said material is thin, the flanges 20 enter said slots deeply, while if it is 100 thicker, they do not enter so far. The appearance of the wicket-casing is not in any way affected by such variation in the door's thickness, since said telescopic arrangement of the flanges and grooves wholly conceals 105 the same.

The ends of the top 16 and of the upper ends of the sides 17, are mitered together, but the lower ends of the sides descend beside the ends of the water-shed 12. Said top and 110

sides are fastened to the door 1 by screws, brads or nails driven through the front strips 19 into the door.

The wicket door 2 is hinged to the top member 5 to swing freely into place against the rabbets 10, and is provided with a latch 21 for locking it, and a hand-pull 22 for closing it.

In using the wicket, the wicket-door 2 is left almost closed, with the spring catch or latch 21 not quite engaged with its socket 23, so that the man bringing the milk or other articles can push the door open with one hand and introduce the articles through the opening with the other. When all are within, he pulls the door 2 tightly closed, and the spring catch engages its socket and locks the wicket-door. After this the latter cannot again be opened from the outside until the householder has removed the articles and slightly opened it.

Although I have spoken of this wicket as especially designed for milk, groceries, and other articles, it should not be forgotten that it is equally useful for the mail-man both for the deposit of large envelops, magazines, and newspapers, and particularly for the parcel-post. For these last purposes, the wicket would be attached to the front door of the house and would need to be provided with a lock and key, a duplicate key being carried by the letter carrier so that he could open the wicket from the outside and deposit mail even where the family were absent for a day and so could not reset the wicket-door.

The claims in this application are made specific to the construction set forth for the reason that in my companion application, Serial No. 843,299, are the generic claims which might otherwise be introduced herein.

What I claim is:

1. The combination with a house-door

having a panel removed, of a wicket comprising an inner frame adapted to be fastened within the opening left by the removal of the said removed panel, said frame having a shoulder resting against the inner surface of the house-door, and a deep groove or slot in its outer surface, and an outer frame having a front strip resting against the outer surface of the house-door, and a flange entering said groove or slot, the telescopic adjustment of said flange in said groove or slot permitting the adaptation of the inner and outer frame members to house-doors of different thicknesses, and a wicket-door hinged to the inner frame.

2. The combination with a house-door having a panel removed, of a wicket comprising a wicket-casing and a wicket-door hinged thereto, said casing consisting of an inner frame and an outer frame, the inner frame embracing top, side and bottom members, the top and side members having each a shoulder resting against the inner surface of the house-door, and the bottom member projecting beyond the outer surface of the house-door and having an overhand descending slightly below the edge of the door-opening, the upper surface of the water-shed slanting downward outwardly, and the outer frame consisting of top and side members each having a front strip resting against the outer surface of the house-door, the lower ends of the side members descending to the level of the under surface of the said bottom member.

In testimony that I claim the foregoing invention, I have hereunto set my hand this 13th day of October, 1914.

WILLIS A. FOGG.
